UNITED STATES PATENT OFFICE

102,029

DESIGN FOR A COMBINED STOOL AND MILK PAIL SUPPORT

Emmett W. Gillaspie, New Castle, Pa.

Application September 12, 1936, Serial No. 64,827

Term of patent 7 years

To all whom it may concern:

Be it known that I, Emmett W. Gillaspie, a citizen of the United States, residing at New Castle, in the county of Lawrence and State of Pennsylvania, have invented a new, original, and ornamental Design for a Combined Stool and Milk Pail Support, of which the following is a specification, reference being had to the accompanying drawing, forming a part thereof, wherein—

Fig. 2 is a side elevation thereof, and

Fig. 3 is an end elevation of the same.

I claim:

The ornamental design for a combined stool and milk pail support substantially as shown.

EMMETT W. GILLASPIE.
